Specification of Letters Patent.

Patented Mar. 9, 1920.

Application filed June 8, 1914. Serial No. 843,865.

To all whom it may concern:

Be it known that we, ELI BROTHERS and JOHN T. LANCASTER, citizens of the United States, residing at Lynn and Beverly, in the county of Essex and State of Massachusetts, respectively, have invented certain Improvements in Upper-Pulling Machines, of which the following description, in connection with the accompanying drawings, is 10 a specification, like reference characters on the drawings indicating like parts in the several figures.

This invention relates to shoemaking machines and particularly to upper pulling machines and is herein shown as embodied in a development of the machine shown and described in Patent No. 1,029,387, granted June 11, 1912 on application of R. F. McFeely.

20 The McFeely machine is organized to pull an upper by power-driven mechanism acting through yielding connections and then come to rest to permit manual adjustments of the upper. The yielding connections are 25 set to give the tension which the operator judges that the upper stock will stand without tearing, tension adjusting wedges being provided for use in quickly resetting the updraw springs for increasing or diminishing the tension which they shall apply 30 according to the strength of the stock that is to be pulled. A limited extent of additional manual pulling may also be and sometimes is effected during this period of rest. 35 To do that the operator reaches up and pushes upward on handles provided on the gripper carrying arms of the updraw levers. The yielding connections expand to retain more or less of this additional pull. It is 40 characteristic of that machine that it pulls over the shoe by means of a yielding tension and holds the upper under tension by yielding mechanism until the upper is fastened. From the time the grippers begin to 45 pull the upper until they release it the updraw springs are acting to stretch the upper and are in condition to react to take up the stretch as the elastic upper responds to their pull. This yielding pulling mechanism has 50 two widely recognized advantages: It renders a power-driven pulling-over machine self adapting within limits to the well-known differences in elasticity of the upper stock of different shoes, and it enables the 55 pulling mechanism to apply to the upper as long as it holds it a continuous tension equal to that at which the updraw springs are set. For example, if the springs are set to apply a tension of eighty pounds they will be compressed by the power-driven mechanism 60 when that tension is reached and will transmit substantially that tension to the upper; and as the upper "gives" the springs will expand to take up the stretch and will continue to apply approximately eighty pounds 65 tension and no less as long as they hold the upper. The organization of the machine shown in the patent is conducive to expeditious work and has given general satisfaction, although the economy of its use is discounted to some extent in many factories by damage produced by tearing uppers which 70 will not stand the tension for which the machine is set when the shoe is subjected to the operation of the machine. Much of this 75 damage could doubtless be avoided if operators possessed or exercised better judgment in recognizing upper stock that will tear, but a part of this danger of tearing it is impractical for the operator to recognize before the upper begins to stretch. In the quick-acting, power-driven machine of that 80 patent there is of course no opportunity for the operator to check the strain and prevent or stop the tearing after the pulling has begun. This fact has been recognized in the art and efforts have been made along two 85 lines to overcome the evil of torn uppers. In the machine of United States Letters Patent No. 1,118,965, granted Dec. 1, 1914, 90 on application of William C. Stewart, manually operated mechanism for gripping and pulling the upper was substituted for the power-driven pulling-over mechanism of the McFeely machine. This machine has an obvious handicap as to capacity and labor cost of the operation. In the machine of United States Letters Patent No. 1,169,414, granted on January 25, 1916, upon the application 95 of R. F. McFeely, a great advance was made 100 by organizing the machine with a pull retarding mechanism that rendered the updraw slow enough to enable the operator to watch it, and by further equipping the machine with a hand lever connected with both 105 side grippers and arranged for the operator to seize during the slow updraw. By the use of this lever the operator can arrest the stretching of the upper produced through the updraw springs whenever he sees that 110

the tension which that particular upper can stand, or should receive, has been reached. The spring pull is retained in this machine; both sides of the shoe are pulled simultaneously so that the operator has to watch both sides and cannot as readily detect the limit of elasticity at either side as if his attention were directed to one side alone; and both sides are pulled to substantially the same extent because the pulling on both sides must be arrested as soon as the limit has been reached on either side.

The present invention approaches the conditions above outlined from a different standpoint and while retaining the advantages of power driving mechanism provides, as an important feature, novel means for pulling an upper at one or more points under such control as to permit the precise tension desired on any particular portion of the upper to be readily obtained without danger of overstraining the upper. The invention in its illustrative embodiment, provides power driven means for operating one gripper independently of others, the machine shown having means for operating the grippers which engage the upper at opposite sides of the shoe independently of each other and under separate control for tensioning differently, as desired, the different respective portions of the upper. In the illustrated embodiment of the invention, moreover, and in accordance with a further important feature, means is provided for imparting a supplemental pull to the upper subsequent to a prior pull which may be effected through readily yieldable connections with all the advantages attendant upon a yielding pull. It is contemplated that the final pull may be effected unyieldingly or substantially unyieldingly, being practically a "dead" pull. In the construction shown the unyielding pull is produced by the power driving mechanism under complete control of the operator, enabling him to check the pull instantly when he sees that the desired or permissible tension has been reached. A very important characteristic of this invention, as it is herein shown as embodied, is that when the pulling movement of the driving mechanism stops the stressing of the upper stops. There are preferably no springs under tension in this mechanism to continue to apply pulling force. The great importance of this as at present advised is that the operator can stop the pull before the point of rupture of the stock is reached with confidence that there are no forces left at work which will cause tearing of the upper. It sometimes happens in the use of a spring pull that the rupture will begin to appear during the period of the machine's rest in consequence of the continued stressing by the updraw springs. If tearing begins while the stock is held by

a spring pull it inevitably continues because the force required to initiate the tearing is more than enough to extend a rent which has been started.

Preferably and as herein shown a separate manual control lever is provided with a handle below the shoe for each side gripper and the final pulling of the two sides of the shoe may, if desired, be effected successively, preferably first on the "inside", or the big toe side of the last, and then on the "outside" of the last. The control lever handles are, however, shown as arranged in such proximity that they can both be actuated simultaneously, to the same or to different extents, and by the one hand if desired. Important safety devices also are provided, as well as means for locking the grippers against retraction from positions to which they are moved and automatic means for restoring the parts, including the grippers, to normal relation at the end of their operation.

Another important feature of the preferred embodiment of the invention is means for producing a step-by-step or intermittent pulling, effected by rapidly-repeated short pulling impulses. Automatically acting locking devices are provided for holding each increment gained by the pulling impulses. These impulses are shown as obtained by the use of ratchet faced friction clutch surfaces which are formed to slip past one another after applying a pulling tension determined by the force with which the operator holds the faces in contact by means of the control lever. The locking devices, with or without the feature of intermittent pulling, hold the upper at the point to which it has been pulled until the machine is restarted for the overdraw of the upper into position to be fastened and only after the upper has been drawn inwardly over the edge of the shoe bottom under unyielding tension sufficiently to bind the upper against said edge are the locking devices released and the grippers permitted to descend toward the face of the shoe bottom for laying the upper down upon the inner-sole. A tighter overdraw, with less loss of tension, is thus obtained than is secured from yieldingly actuated grippers.

Another feature of the invention resides in novel power operated means for moving a gripper or grippers at the will of the operator in a direction to relax the pull upon the upper. In the use of the construction shown, in which the opposite side grippers may each be moved independently in different directions as desired, the operator is thus enabled by power to effect an adjustment of the upper to position it in the correct relation to the last; and still another feature of the invention resides in power operated means for effecting relative adjust-

ment of an upper and a last after the upper has been pulled.

The foregoing novel features of this invention together with certain combinations of parts and details of construction, all of which constitute features of this invention, will now be described in connection with the accompanying drawing in which is illustrated the best embodiment of the invention now known to us, but this machine has not yet had sufficient length of shoe factory operation to demonstrate conclusively that various changes in mechanism may not be desirable for the production of the best commercial machine. The machine shown and to be now described is therefore to be considered as an illustrative example embodying the invention in practical form.

Figure 1 is a side elevation of the machine.

Fig. 2 is a rear end view partially in vertical transverse section, the driving pulley on the main shaft being omitted to facilitate the disclosure of the parts adjacent to it.

Fig. 3 is a perspective view of the control mechanism that is located on the left hand side of the machine.

A general understanding of the construction, organization and operation of the commercial type of pulling-over machine represented in said McFeely Patent No. 1,029,387, will be assumed and this description will therefore be confined to the new mechanisms and the parts closely associated with them.

The base shaft or counter shaft 1 carries a large pinion 2 formed on a constantly running pulley. The pinion 2 drives continuously two gears 3 and 4, Fig. 2, which are mounted on short shafts carrying worms 5 and 6. The worm 5 engages upon the outer or left hand side, viewing Fig. 2, of a worm gear 7 and the worm 6 engages on the outer or right hand side of a worm gear 8. These gears are keyed on vertical shafts 9 and 10 which they drive in opposite directions as indicated by the arrows in Fig. 2. These shafts and their associated parts are alike for the right and left sides of the machine and there is shown in detail in the drawings and will be here described only the parts which are located on that side of the machine which is on the right hand in Fig. 2, and is seen in Fig. 1.

The vertical shaft 10 carries a worm 12 by which it continuously drives a worm gear 14 fast on a horizontal shaft 16 that turns in bearings formed in a bracket secured to the side of the machine head. The shaft 16 continuously drives a spool-shaped hub 18 which is splined on the shaft to move endwise and has on its opposite ends 20, 21 friction clutch members the surfaces of which are preferably irregular or, as shown, toothed. These clutch faces are adapted to engage alternately with similarly formed faces 22, 23 on beveled gears 24, 25. The

surfaces of the clutch members are so formed that they hold until a substantial resistance is encountered and then slip to produce a series of rapidly-repeated, short sharp pulling impulses. The clutch hub 18 has a circumferential groove in which are received blocks on the forks of one arm of a hand lever 28 which is fulcrumed in the bracket at 29 and extends downwardly and forwardly to the front of the machine below the shoe where its end is inturned to constitute a handle 30 located where the operator, standing in normal working position, can engage and manipulate it while he watches the shoe that is being pulled. Raising the handle 30 forces the clutch hub 18 rearwardly along the shaft 16 and presses the friction face 20 of the hub into clutching engagement with the face 22 of the beveled gear 24. Lowering the handle 28 forces the clutch hub 18 forwardly along the shaft 16 and presses its friction face 21 into clutching engagement with the face 23 of the beveled gear 25. The handle and the lever 28 of which it is a part is therefore a shifting device comprising part of manually controllable means for causing motion to be transmitted from the power-driven mechanism of the machine to the beveled gears 24 and 25.

The beveled gears 24 and 25 turn freely on the shaft 16 and are both constantly in mesh with a beveled gear 32 upon a vertical shaft 34 which turns in bearings in the bracket and the upper end of which is formed as a screw 35. The screw 35 extends through a threaded sleeve 36 which is rigidly attached to and projects forwardly from a vertical slide 38, Fig. 1. The slide is movable in a guide 40 attached to the machine head and has rearwardly projecting ears 41, Figs. 1 and 2, between which is confined the end of a stud 44 extending outwardly from the rear end of the usual side gripper lever 45. There may be a relief spring between the stud 44 and the ear 41, as shown in Fig. 1, to prevent breakage of the machine. This spring, however, is very stiff and does not relieve the unyielding pull which this mechanism is designed to transmit to the gripper and upper through the updraw lever 45.

The updraw lever is fulcrumed at 46 and carries the usual side gripper 47 depending from its front end. The rear end of the lever 45 is connected through an adjustably tensioned spring 48 with the slide 49, Fig. 2, which carries a roll standing in a groove 52 in the front face of the brake cam 50, this being the characteristic construction for effecting the usual yielding updraw movement from the cam shaft of the McFeely machine. It is unnecessary particularly to illustrate or to describe the well-known mechanism of that machine consisting of the side grippers to engage the upper at op-

posite sides of the last upheld with its sole face in a plane inclined to the vertical and against a last bottom rest in position for an upper to be engaged by the side grippers and toe gripper and in position to permit the operator to have a substantially unobstructed view of the forward portion of the shoe during the pulling-over operation. Said machine also comprises automatic stopping mechanism to bring the machine to rest, after the upper has been yieldingly pulled, for the purpose of permitting inspection and adjustment of the upper, and mechanism is brought into action when the machine is restarted to seize and hold the shoe while the grippers overdraw the upper and give place to wipers and tackers which fasten the upper in pulled over condition.

As stated, there is on the opposite side of the machine from that shown in Fig. 1 mechanism corresponding to the new mechanism above described as manually controllable by the operator for connecting the opposite side gripper to the power-driven operating mechanism, the handles 30 for the two controlling mechanisms being arranged in proximity as shown in Fig. 2. The machine operates as does the McFeely machine to seize and initially pull the upper yieldingly through the updraw levers and the springs 48 by force transmitted from the cam 50, and another cam 54 for the toe gripper, on the cam shaft 55 of the machine. The updraw springs may be light enough to produce gripping and simply a preliminary pulling or straightening out of the upper, or they may be set to such a tension as to produce as much greater pull as may be desired. The new mechanisms controlled by the handles 30 will be operated while the machine stands otherwise at rest. These mechanisms may be employed for effecting adjustment of the upper transversely about the last and for additionally pulling the upper to complete the stretching required for pulling over the shoe. The completion of the stretching may be accomplished by movement of the two side grippers together or successively and to the same or to different extents. Preferably they will be moved successively and also preferably the gripper on the inner side of the last will be raised first to updraw the upper on that side, which is the more difficult side of the last over which to pull the upper because of the shape of that side of the last, before the updraw is completed on the outer side of the last. The shape of the last allows the upper to be pulled readily down from the cone of the last along the long, gradual slope toward the little-toe or outer side of the last, and the best fitting of the shoe to the last is obtained under some conditions, depending somewhat on the shape of the last, by drawing the upper into final position on the inner side of

the last first and then pulling it as much as may be necessary on the outer side to get it tight and into the correct position on the last. The unyielding or substantially unyielding nature of the supplemental pull provided by the mechanism of this invention enables one side of the shoe to be pulled and held by its side gripper in position while the other side is being pulled. In this important respect the machine of this invention differs from the McFeely machine in which the grippers are yielding at all times.

Provision is made for locking the side grippers which have been yieldingly raised by the initial operation of the machine and also for locking them to hold all that is pulled by the supplemental stretching effected by the use of the mechanism controlled by the handles 30. It will be appreciated that when the shoe is presented to the machine the operator is liable to place the upper farther in the jaws on one side of the shoe than on the other, and for that reason it is important to employ yielding means for initially pulling the upper in order that such means may adjust itself to compensate for the different extents to which the upper is put into the gripper jaws at the opposite sides of the shoe. The illustrated yielding pulling means applies a tension of a definite number of pounds to the upper at one side, for example, and then the spring 48 for that gripper yields while the gripper at the other side continues to pull until a similar tension has been applied to that side of the shoe after which the springs for both grippers yield until the normal stroke of the cam 50 is completed. This produces an approximately equal strength of initial pull at the two sides of the shoe, although it may be an unequal length of pulling movement of the two side grippers, the handles 30 remaining undisturbed and the gears 24, 25 and 32 turning idle during this initial operation. Thereafter, by manipulating the handles 30 the grippers can be caused to move as desired, either together or separately, for further tensioning of the upper.

The locking means above referred to as provided for by this invention is associated with the new mechanism illustrated in Figs. 1 and 3. The front beveled gear 25 has on its hub oppositely faced ratchet wheels 60 and 61 with which coöperate pawls 62, 63 which are connected together by a spring 64, the spring tending to force the pawls into engagement with the respective ratchet wheels. These pawls have heads between which is located an endwise movable cam rod 65 which controls the engagement of the pawls with the ratchet wheels. The rod has depressions 66, 67 coöoperating respectively with the heads of the pawls 62, 63 and into which the spring 64 forces the heads to bring the pawls into engagement

with the ratchets. The cam rod 65 is movable by interlocking engagement with the inner fork, see Fig. 3, of the hand lever 28, which fork has for this purpose an upward extension 68. The cam rod 65 has a plurality of notches in its upper edge and is engaged by a spring wedge pin 70 to hold it and the hand lever 28 in the position to which the operator moves them. When the cam rod stands with its middle notch in engagement with the wedge pin 70, a portion of said rod of full diameter between the depressions 66 and 67 holds both of the pawls out of engagement with the ratchet wheels. This is the normal condition of the machine and prevails during the initial pulling operation. The rods for the two sides of the machine are returned to this central position and the pawls unlocked without attention from the operator after each use. This is done by an arm 72 depending from the hand lever 28 into a fork of a lever 74, Fig. 1. The lever 74 is fulcrumed at 73 and is raised by a connection with the cross-head 75, Fig. 2, on the vertical rod 76 which carries the brake shoe 77 and controls the starting and stopping mechanism of the machine, the connection comprising a link 75' which is pivoted to the lever and the cross-head. This rod is raised by mechanism actuated by a foot treadle 78 when the machine is restarted to drive the fastening tacks, as explained more fully in United States Letters Patent No. 791,986, granted on June 6, 1905, upon an application of R. F. McFeely, and the walls of the fork 74, by their engagement with the roll on the arm 72 of lever 28, return the lever and thereby the cam rod 65 to central position. In using the invention, after the upper has been initially pulled and the machine come to rest, the operator can throw in the locking pawls 63 for both side grippers by slightly depressing the levers 28. The cam rods 65 are shown as having holding notches at either side of the central notch and by means of which the spring pins 70 will hold the cam rods in position for the pawls to lock the side grippers against downward movement. By further depression of either one of the levers 28, the side gripper associated with that lever may be connected with the power mechanism which will be made to uplift the gripper unyieldingly and produce a further positive pull upon the upper. This is done while the operator stands in position to watch the shoe and terminate the pulling movement as soon as the upper has been pulled by the moving gripper as far as the operator's judgment indicates that it needs to be pulled. The lever 28 associated with the other side gripper may then be similarly depressed and the upper thereby positively pulled at the opposite side of the shoe. The pawls will perform an important office in holding from downward movement the gripper which has been yieldingly uplifted for initially pulling the upper and preventing such displacement as would otherwise occur while the gripper at the opposite side of the machine is caused to pull the upper further. It is obvious that both levers 28 may be depressed at the same time and thereby the new mechanism caused to uplift both side grippers positively at the same time. Pulling movement effected by either side gripper while the other side gripper is held stationary tends to adjust the upper transversely about the last and may be employed for making such transverse adjustment of the upper as is necessary to locate the upper properly upon the last, the other gripper being simultaneously lowered, if desired, upon the uplifting movement of its controlling lever, as hereinafter explained, to facilitate the adjustment. Adjustment of the upper longitudinally about the last is effected by the usual tip straightening mechanism of the McFeely machine which is operated by the lever 292 shown in Fig. 1. Instead of depressing either hand lever 28 it may be lifted whereupon the clutch member 18 will be engaged with the gear 24 and rotate the screw 35 in the direction for lowering the gripper. Such lifting of the lever 28 adjusts the cam rod 65 for lifting the pawl 63 which prevents lowering of the gripper and throwing into operation the pawl 62 which prevents uplifting of the gripper. The new mechanism controlled by the levers 28 can therefore be used to depress the grippers and relax the tension, which has been applied to the upper, whenever that becomes necessary. This movement can be carried far enough to lower the grippers to initial position and cause them to release the upper.

As previously explained, the teeth on the coöperating clutch faces 20, 22 and 21, 23 are so formed that a relative slip between the clutch members takes place when a predetermined resistance is encountered, whereby there is produced an intermittent pull consisting of rapidly-repeated, short sharp pulling impulses as distinguished from a steady pull such as would be produced by non-slipping or by smooth clutching surfaces. These intermittent pulling impulses are peculiarly effective in stretching shoe uppers without tearing them.

To prevent accidents which might occur from movement of the levers 28 at inopportune times each cam rod 65 is extended rearwardly and provided with a head 82 which coöperates with a rod 80. The rods 80 depend from a cross-bar on the cam slide 49, see Fig. 2. The cam slide 49 positions the rods 80 during the upper pulling movement and locates notches 81 in position to

allow manipulation of the cam rods 65 while the machine is at rest with the shoe under tension. At all other times the rods 80 prevent manipulation of cam rods 65 and therefore of the hand levers 28 in a direction to cause the grippers to pull the upper.

To avoid danger of excessive pulling by the new mechanism constituting the manually controllable connection between the 10 power-driven operating mechanism and the grippers, special precaution has been taken. The arm 72 of hand lever 28 carries a stud which is located between spring-pressed plungers 85, Fig. 3, and in order to force 15 the clutch members into position the resistance of one or the other of these spring plungers must be overcome and that plunger tends all the time to force the clutch members out of engagement. Furthermore, 20 each of the pinions 24, 25 is provided with a sliding rod or pin 90 which is adapted to engage an end face of the clutch member 18 and is so located with relation to a wedge 92 as to be thrust endwise by the 25 wedge when the pinion carrying it has been turned far enough to thrust the sleeve 36 to a certain limit of movement. This pin 90 and wedge 92 constitute an automatic throw-out for always disengaging the clutch 30 members when the limit of possible safe movement is approached and despite any pressure which the operator may unwisely apply to the hand levers 28.

When the starting treadle 78 is depressed 35 the machine starts at once as soon as the brake is lifted but on account of a slight lost motion and the fact that the clutch becomes effective before the brake rod arrives at its upper limit of movement the fork 74 40 does not effect release, through the described connections, of the gripper locking pawls until after the cam shaft 55 has begun to turn and the tackers have moved, or begun to move, the grippers inwardly for over- 45 drawing the upper. Therefore the over-draw movement is made to occur, or to begin, with the grippers locked up under hard tension, and by reason of this fact and the inertia of the gripper levers and their 50 connections tending to render tardy any response to the strain of the upper when they are suddenly unlocked the overdraw is made tighter than heretofore.

The manner in which the invention may 55 be used has been sufficiently explained in connection with the foregoing description of the illustrated mechanism which constitutes the present preferred embodiment of the invention. It is obvious that there are 60 features of the invention which may be used independently of others and that some features may be used in upper pulling machines differing radically from the illustrated machine.

We claim as new and desire to secure by 65 Letters Patent of the United States:—

1. A pulling-over machine having, in combination, grippers for engaging the forepart of an upper upon opposite sides of a last, power-driven mechanism for moving the 70 side grippers to pull the upper, and separately controllable connections between the respective grippers and said mechanism by which said mechanism may be made to cause additional movements of the grippers for increasing or decreasing the pulling strain. 75

2. A pulling-over machine having, in combination, grippers for engaging the forepart of an upper upon opposite sides of a last, power-driven operating mechanism connected 80 with said grippers to cause them to pull the upper and come to rest holding the upper about the last, and separately controllable connections between said mechanism and each of said side grippers for rendering 85 said mechanism effective to move the grippers independently of each other for further pulling the upper.

3. A pulling-over machine having, in combination, grippers for engaging the forepart 90 of an upper upon opposite sides of a last, power-driven operating mechanism for causing the grippers to seize and pull the upper, and then come to rest holding the upper under tension, means by which the grippers 95 and the last may be relatively moved for adjusting the upper, and connections between said power mechanism and one of the grippers for rendering said mechanism effective to move said gripper for further pulling the 100 upper without similarly moving the other gripper.

4. A pulling-over machine having, in combination, grippers for engaging the forepart of an upper upon opposite sides of a last, 105 power-driven operating mechanism for causing the grippers to seize and pull the upper, and connections separately controllable manually with respect to one of said grippers for causing said power mechanism to move said 110 gripper for further pulling the upper without similarly moving the other gripper.

5. A pulling-over machine having, in combination, grippers movable to seize an upper at opposite sides of a last and pull the upper, 115 power-driven operating mechanism, and separately controllable driving connections from said mechanism to said opposite side grippers respectively through which said grippers can be made to pull the upper to 120 extents determined by the operator for each side of the shoe.

6. A pulling-over machine having, in combination, grippers movable to seize an upper at opposite sides of a last and pull the upper, 125 power-driven operating mechanism, a manually controllable driving connection by which said mechanism can be made to operate one

side gripper, and a manually controllable driving connection by which said mechanism can be made to operate the other side gripper.

- 5 7. A pulling-over machine having, in combination, grippers movable to seize an upper at opposite sides of a last and pull the upper, power-driven operating mechanism, and driving connections separately controllable 10 with respect to each of said grippers for rendering said mechanism effective to move either or both of said grippers in directions to pull the upper.

8. A pulling-over machine having, in combination, grippers movable to seize an upper at opposite sides of a last and pull the upper, power-driven operating mechanism, and connections through which the operator can cause said mechanism to move the grippers 20 to pull the upper at one side of the shoe and then at the other side.

9. A pulling-over machine having, in combination, grippers movable to seize an upper at opposite sides of a last and pull the upper, power-driven operating mechanism, connections through which the operator can cause said mechanism to move the grippers to pull the upper at one side of the shoe and then at the other side, and means for locking the 30 gripper first moved from reverse movement while the second gripper is made to pull.

10. A pulling-over machine having, in combination, grippers for engaging an upper at opposite sides of a last, power-driven 35 operating mechanism, yielding connections through which the grippers are caused to apply a yielding pull to the upper, and unyielding connections through which the grippers may be thereafter caused by said power-driven mechanism to apply an unyielding pull to the upper.

11. A pulling-over machine having, in combination, a shoe bottom rest, a gripper for engaging the shoe upper, power driven 45 operating mechanism, yielding connections through which the gripper is caused to apply a yielding pull to the upper, and unyielding connections through which the gripper may be thereafter caused by said power driven mechanism to apply an unyielding pull to the upper.

12. A pulling-over machine having, in combination, grippers for engaging an upper at opposite sides of a last, power-driven 55 operating mechanism, yielding connections through which the grippers are moved to apply a pull having a certain force determined by the strength of the yielding connections, and other connections through 60 which the grippers may be moved by said mechanism to apply a force determined by the operator.

13. A pulling-over machine having, in combination, grippers for engaging an upper 65 at opposite sides of a last, power-driven

operating mechanism, yielding connections through which the grippers are moved to apply a pull having a certain force determined by the strength of the yielding connections, and other connections through 70 which the grippers may be moved by said mechanism to apply a force determined by the operator separately for each side of the shoe.

14. A pulling-over machine having, in combination, grippers for engaging an upper at opposite sides of a last, power-driven 75 operating mechanism, connections from said mechanism to the grippers whereby they are caused to apply substantially the same pulling force to the upper at each side of the shoe approximately unaffected by unequal insertion of the upper stock into the grippers at the two sides of the last, and unyielding connections from said mechanism to the 80 85 grippers through which subsequent pulling force may be applied to the upper.

15. A pulling-over machine having, in combination, grippers for engaging an upper at opposite sides of a last, power-driven 90 operating mechanism, connections from said mechanism to said side grippers through which they updraw the upper with equal force on the two sides of the shoe, and additional connections through which said mechanism may be made to updraw the upper on each side of the shoe positively and to extents separately determined for each side of the shoe by the operator.

16. A pulling-over machine having, in combination, grippers for engaging an upper at opposite sides of a last, power-driven 100 operating mechanism, and connections from said mechanism to the grippers through which said side grippers are made to updraw 105 yieldingly and then positively.

17. A pulling-over machine having, in combination, grippers for engaging an upper at opposite sides of a last, power-driven 110 operating mechanism, and connections from said mechanism to the grippers through which said side grippers are made to updraw yieldingly and then positively, the yielding pull being predetermined by the adjustment of the machine and the positive 115 pull being controllable by the operator as the operation proceeds.

18. A pulling-over machine having, in combination, grippers for engaging an upper at opposite sides of a last, power-driven 120 operating mechanism, and connections from said mechanism to the grippers through which said side grippers are made to updraw yieldingly and then unyieldingly to pull one side and then the other side with 125 opportunity so to pull the two sides to such different extents as the judgment of the operator indicates is required for the particular shoe.

19. A pulling-over machine having, in 130

- combination, grippers for engaging an upper at opposite sides of a last, power-driven operating mechanism, and connections from said power mechanism to the grippers for effecting simultaneous pulling by the side grippers and permitting said mechanism to be caused to operate the grippers one at a time for further pulling of the upper.
20. A pulling-over machine having, in combination, grippers for engaging an upper at opposite sides of a last, power-driven operating mechanism, connections from said power mechanism to the grippers for applying first a predetermined initial pulling force and then permitting separate pulling movements of the grippers to be applied by said mechanism under control of the operator, and controlling means for said separate movements.
- 20 21. A pulling-over machine having, in combination grippers arranged to engage an upper at opposite sides of a last, power driving mechanism, and connections controllable by the operator for causing said mechanism to operate the said grippers to pull the upper at the two sides of the shoe to relatively different extents which may be determined by the operator during the pulling operation.
- 30 22. A pulling-over machine having, in combination, grippers arranged to engage an upper at opposite sides of a last, power driving mechanism, and connections from said mechanism to one side gripper and to the other side gripper constructed and arranged to permit separate control by the operator for causing said mechanism to operate the grippers on the two sides of the shoe to pull the upper to relatively different extents.
- 40 23. A pulling-over machine having, in combination, grippers arranged to engage an upper at opposite sides of a last, power driving mechanism, and connections including separate control levers for each side gripper having handles arranged in proximity permitting simultaneous engagement by one hand of the operator or separate manipulation, said connections providing means through which said mechanism can be made to operate one or the other or both side grippers at the will of the operator.
- 50 24. A pulling-over machine having, in combination, grippers arranged to engage an upper at opposite sides of a last, and power driving mechanism connected with the grippers and arranged for operation to pull the upper positively on one side of the shoe and lock it and then to pull the upper on the second side while that on the first side is held unyieldingly by the machine.
- 60 25. A pulling-over machine having, in combination, grippers arranged to engage an upper at opposite sides of a last, and power driving mechanism connected with the

grippers and arranged to be controlled by the operator to cause the grippers to initially pull the upper to the last, then to pull the upper on one side and hold it and thereafter to pull it on the opposite side.

70

26. A pulling-over machine having, in combination, grippers arranged to engage an upper at opposite sides of a last, power operating mechanism therefor arranged to come automatically to rest with the grippers holding the upper under tension, and means by which the operator can cause said mechanism to move the grippers to increase the pull on the upper and again come to rest holding the upper under tension.

80

27. A pulling-over machine having, in combination, grippers arranged to engage an upper at opposite sides of a last, power operating mechanism therefor arranged to come automatically to rest with the grippers holding the upper under tension, and means by which the operator can cause said mechanism to move either gripper separately to change the tension on the upper.

85

28. A pulling-over machine having, in combination, grippers arranged to engage an upper at the toe and at opposite sides of the forepart of a last, power operating mechanism therefor arranged to come automatically to rest with the grippers holding the upper under tension, and means by which the operator can cause said mechanism to move a gripper to change the tension on the upper.

90

29. A pulling-over machine having, in combination, grippers arranged to engage an upper at opposite sides of a last, power operating mechanism therefor arranged to come automatically to rest with the grippers holding the upper under tension, and means by which the operator can cause said mechanism to move the grippers to pull one side and then the other of the upper.

100

30. A pulling-over machine having, in combination, grippers arranged to engage an upper at opposite sides of a last, power operating mechanism therefor arranged to come automatically to rest with the grippers holding the upper under tension, and means arranged for optional use and which can be manipulated to cause said power mechanism further to move either gripper in the direction of the tension.

110

31. A pulling-over machine having, in combination, grippers arranged to engage an upper at opposite sides of a last, power operating mechanism therefor arranged to come automatically to rest with the grippers holding the upper under tension, and connections through which said mechanism applies first a yielding pull to the upper and then an unyielding pull.

120

32. A pulling-over machine having, in combination, grippers arranged to engage an upper at opposite sides of a last, power

130

operating mechanism therefor, and connections through which said mechanism applies first a yielding pull to the upper equally through both side grippers spring-actuated together and then an unyielding pull determinable in extent for each gripper by the operator.

33. A pulling-over machine having, in combination grippers arranged to engage an upper at opposite sides of a last, power operating mechanism therefor arranged to come automatically to rest with the grippers holding the upper under tension, and connections through which said mechanism applies first an initial pull to the upper substantially equally through both side grippers and then a second pull determinable in extent for each gripper separately.

34. A pulling-over machine having, in combination, grippers arranged to engage an upper at opposite sides of a last, power operating mechanism therefor, and connections through which said mechanism applies first an initial pull to the upper substantially equally through both side grippers and then a second pull determinable as between the two side grippers by the operator as to the order of actuation of the two grippers.

35. A pulling-over machine having, in combination, grippers arranged to engage an upper at opposite sides of a last, power operating mechanism therefor arranged to come automatically to rest with the grippers holding the upper under tension, and manually controlled connections between the power mechanism and said grippers by which the grippers can be actuated by said mechanism in the relative directions to adjust the upper transversely about the last.

36. A pulling-over machine having, in combination, grippers arranged to engage an upper at opposite sides of a last, power operating mechanism therefor arranged to come automatically to rest with the grippers holding the upper under tension, and manually controlled connections between the power mechanism and said grippers by which said power mechanism can be made to actuate the grippers to adjust the upper about the last.

37. A pulling-over machine having, in combination, pulling-over means, power mechanism operating to cause the pulling-over means to pull the upper and come to rest holding the upper under tension for inspection, and means arranged for manual control after the operation of said power mechanism to cause said mechanism to apply the power for adjusting the pulled upper and the last relatively after such inspection.

38. A pulling-over machine having, in combination, pulling-over means including toe and side grippers, a cam shaft and con-

nections through which the grippers are operated to pull the upper and then come to rest holding the upper under tension for inspection and adjustment, power driven mechanism, and manually controllable connections from said mechanism to the side grippers by which they can be manipulated to act further on the upper while the cam shaft remains at rest.

39. A pulling-over machine having, in combination, pulling-over means including grippers and power-driven operating mechanism by which the grippers can be moved to stretch the upper to a definite extent separately determined by the operator for each gripper during the stretching operation and the movement of the grippers then be arrested and further stretching avoided while the grippers hold the upper under tension.

40. A pulling-over machine having, in combination, pulling-over means including grippers and power-driven operating mechanism transmitting an unyielding pull to the upper through the grippers, and automatically acting locking means for securing the grippers with the upper under tension in the position to which the said mechanism moves the grippers.

41. A pulling-over machine having, in combination, pulling-over means including grippers arranged to engage the upper at opposite sides of a last, and operating mechanism for effecting updrawing movement of the grippers by repeated short separate upward impulses during a continuous movement of a portion of said mechanism.

42. A pulling-over machine having, in combination, pulling-over means including grippers arranged to engage the upper at opposite sides of a last, and power-driven operating mechanism constructed and arranged to impart to the grippers rapidly-repeated short separate updrawing impulses.

43. A pulling-over machine having, in combination, grippers arranged to be engaged with an upper at opposite sides of a last, and operating mechanism adapted to be temporarily connected with the grippers and constructed and arranged to impart thereto while so connected a series of short rapidly-repeated pulling impulses, and means for locking the grippers against reverse movement.

44. A pulling-over machine having, in combination, grippers arranged to be engaged with an upper at the opposite sides and the toe of a last, and operating mechanism including a driven member and a tooth-faced friction driving connection between said member and a gripper adapted to impart to the gripper a pulling impulse as the teeth engage and a dwell as the teeth slip and to repeat the pulling impulse and

- the dwell a plurality of times for producing step-by-step pulling of the upper.
45. An upper pulling machine having, in combination, a gripper, and power driven operating mechanism constructed to impart to the gripper a step-by-step pulling movement consisting of an indefinite but manually terminable series of short rapidly-repeated pulling impulses.
- 10 46. An upper pulling machine having, in combination, a gripper, operating mechanism for imparting to the gripper a step-by-step pulling movement consisting of an indefinite but manually terminable series of 15 short rapidly-repeated pulling impulses, and automatically acting locking means for retaining the pull effected by the pulling impulses.
- 20 47. An upper pulling machine having, in combination, a gripper, and operating mechanism therefor including toothed friction driving connections with the gripper constructed and arranged to impart rapidly alternating pulling impulses and dwells as 25 teeth engage and then slip and reengage.
- 30 48. An upper pulling machine having, in combination, a gripper, operating mechanism therefor including toothed friction driving connections with the gripper constructed and arranged to impart rapidly alternating pulling impulses and dwells as teeth engage and then slip and reengage, and manually controlled means for determining the force with which said toothed 35 friction driving connections engage.
- 40 49. An upper pulling machine having, in combination, a gripper and operating mechanism therefor including a driven member and irregular faced slipping driving connections between said member and the gripper, and means by which the operator can vary the force of the engagement of said irregular faced slipping driving connections to produce short rapidly-repeated 45 pulling impulses in the gripper of varying intensity.
- 50 50. A pulling-over machine having, in combination, grippers, means for yieldingly actuating them to effect initial tensioning, and means for unyieldingly operating the grippers to complete the tensioning and for locking them to hold the tension.
- 55 51. A pulling-over machine having, in combination, grippers, operating mechanism including springs through which an initial tension equal to the strength of the springs is applied through the grippers to the upper and the springs are compressed, and additional means by which further tension exceeding the strength of the springs is applied through the grippers to the upper and the grippers are thereby taken out of control of the springs, and means for locking the grippers against tension slackening 60 movement.
52. A pulling-over machine having, in combination, grippers and power-driven operating mechanism, and spring connections through which an initial tension equal to the strength of the spring connections is applied to the upper and the machine is brought to rest for inspection of the shoe with the spring connections continuing to act with the force stored therein to stretch the upper further, and additional means for 70 unyieldingly applying such a substantially greater degree of tension to the upper as inspection of the shoe indicates to be needed.
53. A pulling-over machine having, in combination, grippers arranged to engage an upper at opposite sides of a last, means for supporting the last with its bottom face upward in a plane at an oblique angle to the vertical, said parts being constructed and 85 arranged to permit the operator to have a substantially unobstructed view of the forward portion of the shoe during the pulling-over operation, power-driven operating mechanism for the grippers arranged to 90 come to rest with the grippers yieldingly holding the upper under tension, and means connected with the respective side grippers for manipulating them up and down and having separate controlling members for the 95 respective grippers extending below the shoe in position to be engaged and manipulated by the hands of the operator while he continues in normal position to watch the effect of adjustment upon the shoe upper. 100
54. A pulling-over machine having, in combination, grippers arranged to engage an upper at opposite sides of a last, power-driven operating mechanism for the grippers arranged to come to rest holding the 105 upper under tension for inspection and adjustment of the upper, means for further moving the grippers while said operating mechanism is at rest, and automatically acting locking means for each gripper. 110
55. A pulling-over machine having, in combination, grippers arranged to engage an upper at opposite sides of a last, power-driven operating mechanism for the grippers arranged to come to rest holding the 115 upper under tension for inspection and adjustment of the upper, means for moving the grippers while said operating mechanism is at rest, and means adapted to be rendered operative or inoperative for each gripper 120 and acting while operative to secure the gripper in any position to which it has been moved.
56. A pulling-over machine having, in combination, grippers arranged to engage 125 an upper at opposite sides of a last, power-driven operating mechanism for the grippers arranged to come to rest holding the upper under tension for inspection and adjustment of the upper, means for moving the 130

grippers while said operating mechanism is at rest, and devices to lock the grippers against upward movement when they are moved downwardly and to lock the grippers 5 against downward movement when they have been moved upwardly.

57. A pulling-over machine having, in combination, grippers arranged to engage an upper at opposite sides of a last, power-driven operating mechanism for the grippers arranged to come to rest holding the upper under tension for inspection and adjustment of the upper, and additional power-driven mechanism for moving the 10 grippers downwardly to relax tension while the first-mentioned mechanism remains at rest.

58. A pulling-over machine having, in combination, grippers arranged to engage an upper at opposite sides of a last, power-driven operating mechanism for the grippers arranged to come to rest holding the upper under tension for inspection and adjustment of the upper, and additional power-driven 15 mechanism to move the grippers while the first-mentioned mechanism remains at rest.

59. A pulling-over machine having, in combination, grippers arranged to engage an upper at opposite sides of a last, power-driven operating mechanism for the grippers arranged to come to rest holding the upper under tension for inspection and adjustment of the upper, and manually controllable means by which one gripper can be moved 30 to change the pull exerted by it and the gripper at the opposite side of the last can be locked against movement in the direction in which it would be liable to go in response to such change of pull.

40 60. A pulling-over machine having, in combination, grippers arranged to engage an upper at opposite sides of a last, power-driven operating mechanism for the grippers arranged to come to rest holding the upper under tension for inspection and adjustment 45 of the upper, said grippers being movable to readjust the upper, devices to lock the grippers with the upper in readjusted position, and means arranged to unlock the 50 grippers in time to avoid interference with the operations of overdrawing and securing the upper.

61. A pulling-over machine having, in combination, grippers arranged to engage an upper at opposite sides of a last, power-driven operating mechanism for the grippers arranged to come to rest holding the upper under tension for inspection and adjustment of the upper, said grippers being movable 55 to readjust the upper, devices to lock the grippers with the upper in readjusted position, and means for unlocking the grippers without special attention from the operator.

62. A pulling-over machine having, in combination, means for pulling-over an

upper including grippers and operating mechanism therefor, means for locking the grippers against a movement in the direction of strain while they hold the upper under tension, means for performing a subsequent operation, and means for unlocking the grippers as an incident to said subsequent operation. 70

63. An upper pulling machine having, in combination, a last rest, an upper engaging gripper, a power-driven actuator, and connections therefrom to the gripper including a screw and coöperating threaded sleeve and means for producing relative rotation of said screw and sleeve to lift the gripper, for 75 pulling the upper, said means being arranged for manual control to vary the extent of the movement of the gripper.

64. An upper pulling machine having, in combination, a last rest, an upper engaging gripper, a power-driven actuator, and connections therefrom to the gripper including a screw and coöperating threaded sleeve, and means for causing the power mechanism to turn the screw and sleeve relatively for 80 raising or lowering the gripper, to vary the tension of the upper, said means being arranged for manual control to determine the extent of movement of the gripper. 85

65. An upper pulling machine having, in combination, a last rest, an upper engaging gripper, a power-driven actuator, and connections therefrom to the gripper including a screw and coöperating threaded sleeve, 90 and a manually controllable irregular-faced friction clutch between the actuator and said parts, the friction faces of the clutch being adapted to slip for intermittently rotating the screw and producing rapidly-repeated 95 pulling impulses in the gripper.

66. An upper pulling machine having, in combination, a last rest, an upper engaging gripper, a power-driven actuator, and connections therefrom to the gripper including 100 means for moving the gripper in a series of rapidly-repeated short sharp pulling impulses, and means to hold the upper from slackening between said impulses. 110

67. An upper pulling machine having, in combination, a last rest, an upper engaging gripper, a power-driven actuator, and connections therefrom to the gripper including means constructed and arranged to effect a continuous pull until the upper is tightened 115 around the last and then to impart to the gripper a series of short sharp rapidly-repeated pulling impulses for stretching the upper.

68. An upper pulling machine having, in combination, a last rest, an upper engaging gripper, a power-driven actuator, and connections therefrom to the gripper including means to impart an initial pulling movement 120 to the gripper and come to rest and means 125 to

controllable by the operator to cause said power-driven actuator to impart a further pulling movement in the same direction, the latter movement being manually terminable.

- 5 59. A pulling-over machine having, in combination, grippers arranged to engage an upper at opposite sides of a last, power-driven operating mechanism for the grippers arranged to come to rest holding the 10 upper under tension for inspection, and manually controllable connections between a gripper and said mechanism for imparting to said gripper a series of rapidly-repeated short pulling impulses for additionally pulling the upper.

- 60 69. A pulling-over machine having, in combination, grippers arranged to engage an upper at opposite sides of a last, power-driven operating mechanism for the grippers arranged to come to rest holding the upper under tension for inspection, and connections from said power-driven mechanism for imparting to a gripper a manually terminable series of rapidly-repeated short pulling impulses for additionally stretching the upper.

- 70 71. A pulling-over machine having, in combination, a rest for a last, grippers arranged to engage the upper at opposite sides 30 of the last, operating means for the grippers, and additional operating means including power-driven actuators arranged respectively at the opposite sides of the machine and arranged to be manually connected with the side grippers for use in additionally stretching the upper.

- 71 72. A pulling-over machine having, in combination, grippers for engaging an upper at opposite sides of a last, power-driven 40 operating mechanism, connections from said mechanism to said side grippers through which they updraw the upper with equal force on the two sides of the shoe, and additional mechanism by which said side grippers may be made to updraw the upper on each side of the shoe positively and to extents separately determined for each side of the shoe by the operator.

- 72 73. A pulling-over machine having, in combination, grippers arranged to engage an upper at opposite sides of a last, a power-driven operating member, and separately controllable connections from said power-driven operating member to the grippers on opposite sides of the last through which said side grippers may be power driven independently of one another to pull the upper.

- 74 74. A pulling-over machine having, in combination, grippers arranged to engage an upper at opposite sides of a last, a power-driven operating member, and separately controllable connections from said power-driven operating member to the grippers on opposite sides of the last through which said grippers may be power driven to pull the

upper independently of one another and to relatively different extents controllable by the operator.

75 75. A pulling-over machine having, in combination, grippers arranged to engage an upper at opposite sides of a last, and operating mechanism for the grippers arranged for use to cause the grippers to pull the upper on one side of the shoe and hold it unyieldingly and then to pull the upper on the second side while that on the first side is held by the machine from movement transversely around the last.

76 76. A pulling-over machine having, in combination, grippers arranged to engage an upper at opposite sides of a last, and operating mechanism for the grippers arranged for use to cause the grippers to pull the upper on one side of the shoe and hold it unyieldingly and then to pull the upper on the second side while that on the first side is held by the machine from movement transversely around the last, said mechanism being arranged to permit its use to pull the upper on opposite sides of the last alternately and successively and to hold the upper securely on each side from drawing back in response to pull applied at the other side.

77 77. A pulling-over machine having, in combination, grippers arranged to engage an upper at opposite sides of a last, power operating mechanism therefor, and connections through which said power mechanism applies first a yielding pull to the upper and then an unyielding pull and holds the upper under tension with said mechanism at rest.

78 78. A pulling-over machine having, in combination, grippers arranged to engage an upper at opposite sides of a last, power operating mechanism therefor, and connections through which said mechanism applies first a yielding pull to the upper equally through both side grippers and then an unyielding pull which is separately determinable in extent for each side gripper.

79 79. A pulling-over machine having, in combination, grippers arranged to engage an upper at opposite sides of a last, power operating mechanism therefor arranged to come automatically to rest with the grippers holding the upper under tension, and connections through which said mechanism applies first an initial pull to the upper substantially equally through both side grippers and is adapted then to apply a further positive pull to one of the side grippers.

80 80. A pulling-over machine having, in combination, grippers arranged to be engaged with an upper at opposite sides of a last, and operating mechanism adapted to be temporarily connected with the grippers and constructed and arranged to impart thereto while so connected a series of short rapidly-repeated pulling impulses.

81 81. An upper pulling machine having, in

- combination, a gripper and power driven operating mechanism comprising co-operating portions constructed and arranged to impart to the gripper a step-by-step pulling movement consisting of short rapidly-repeated pulling impulses each advancing the gripper in the direction of the strain. 5
82. An upper pulling machine having, in combination, a gripper and power operating mechanism for imparting to the gripper through substantially unyielding connections a step-by-step pulling movement consisting of short rapidly-repeated pulling impulses each advancing the gripper in the direction of the strain. 10
83. A pulling-over machine having, in combination, grippers arranged to engage an upper at opposite sides and the toe of a last, power-driven operating mechanism for the grippers arranged to come to rest with the grippers holding the upper under tension for inspection and adjustment of the upper, and additional power-driven mechanism adapted to move a gripper downwardly to relax tension while the first-mentioned mechanism remains at rest. 15
84. A pulling-over machine having, in combination, grippers arranged to engage an upper at opposite sides and the toe of a last, power-driven mechanism including an updraw cam for the grippers arranged to come to rest with the grippers holding the upper under tension for inspection and adjustment of the upper, and additional power-driven mechanism adapted to move a gripper to change the updrawing tension on the upper while the updraw cam remains at rest. 20
85. A pulling-over machine having, in combination, grippers for engaging an upper at a plurality of separate points and stretching it over a last, operating mechanism for moving the grippers yieldingly to updraw the upper and hold it under tension, means by which an individual gripper may be further moved for additionally tensioning the upper, and means for securing the gripper to maintain the additional tension. 25
86. A pulling-over machine having, in combination, grippers for engaging an upper at a plurality of separate points and stretching it over a last, operating mechanism for initially pulling the upper, and power driving mechanism under complete control of the operator to effect a supplemental pull and arranged to enable the operator to check the pull instantly when he sees that the desired or permissible tension has been reached. 30
87. A pulling-over machine having, in combination, grippers for engaging an upper at a plurality of separate points and stretching it over a last operating mechanism for initially pulling the upper, power driving mechanism under control of the operator to effect a supplemental pull and arranged to enable the operator to check the pull instantly when he sees that the desired or permissible tension has been reached, and means to stop the stressing of the upper when the pulling movement of the actuating mechanism stops whereby rupture of the upper stock, after said mechanism has stopped is avoided. 35
88. A pulling-over machine having, in combination power-driven operating mechanism, and side grippers having connections therewith which are under separate manual control to cause the grippers to be operated by said mechanism to pull the upper first on one side of the last and then on the other side of the last. 40
89. A pulling-over machine having, in combination, power-driven operating mechanism and side grippers having connections therewith which are under separate manual control to adapt the machine for pulling uppers first on one side of the last and then on the other side of the last, and means for holding the gripper that first pulls from reverse movement while the other gripper is pulling. 45
90. A pulling-over machine having, in combination, side grippers and operating mechanism controllable by the operator during the pulling operation for pulling the upper on opposite sides of the shoe to different extents and means for restoring the grippers to balanced relation as an incident to their return to starting position. 50
91. An upper pulling machine having, in combination, a gripper and power-driven operating mechanism therefor including friction clutching surfaces formed with alternating inclines and depressions to hold until a substantial resistance is encountered and then to slip past a depression to another incline to produce an intermittent pulling movement of the gripper. 55
92. An upper pulling machine having, in combination, a gripper and power-driven operating mechanism therefor including friction clutching surfaces formed with alternating inclines and depressions to hold until a substantial resistance is encountered and then to slip past a depression to another incline to produce an intermittent pulling movement of the gripper, and manually controlled means for pressing the clutching surfaces together to govern the pulling force by increasing or diminishing the resistance which will be overcome before slipping occurs. 60
93. An upper pulling machine having, in combination, a gripper and power-driven operating mechanism therefor including a driven clutch hub, beveled gears having clutching faces adapted to be engaged alter- 65

natively by the clutch hub, a screw shaft having a beveled gear meshing with the first-mentioned gears, a screw sleeve on said shaft, connections from the sleeve to the gripper, and shifting means for the clutch hub to cause the gripper to be raised or lowered.

94. A pulling-over machine having, in combination, grippers for engaging an upper at opposite sides of a last and operating mechanism therefor including a driven gear, gear and worm and shaft connections to opposite sides of the machine and associated with each of such connections a clutch hub, 10 beveled gears located at opposite ends of the hub and having clutching faces, a screw shaft having a beveled gear engaging said clutch-faced gears, a screw sleeve connected with the gripper on the adjacent side of the machine, and a clutch hub controller located where the operator can engage it while standing in position to watch the effect of the pulling movement produced on the shoe by the gripper driven by the described 20 mechanism.

95. An upper pulling machine having, in combination, a gripper and power-driven means to impart updrawing and overdrawing movements to the gripper including 30 means to give an unyielding quality to the final portion of the updrawing movement and to lock the gripper up and unlock it only after the overdrawing movement has begun.

96. An upper pulling machine having, in combination, a gripper and power driven means to impart updrawing and overdrawing movements to the gripper including means to give an unyielding quality to the 40 final portion of the updrawing movement.

97. An upper pulling machine having, in combination, a gripper and power-driven means to impart updrawing and overdrawing movements to the gripper including 45 means to give an unyielding quality to the final portion of the updrawing movement and to lock the gripper up and come to rest, means to restart the machine for the overdrawing operation and means arranged to 50 unlock the unyielding updraw only after the overdraw has begun.

98. An upper pulling machine having, in combination, a gripper and power-driven means to impart updrawing and overdrawing 55 movements to the gripper including means to give an unyielding quality to the final portion of the updrawing movement and to lock the gripper up and come to rest, a restarting treadle and connections for 60 causing the overdraw movement to take place, and means operated by movement of the starting treadle to cause release of the unyielding updraw tension to take place subsequent to the initiation of the overdraw.

99. A pulling-over machine having, in combination, opposed side grippers and operating mechanism therefor to produce for updrawing the upper a yielding pull and then a dead pull and to overdraw the upper with a dead pull and then release the grippers from the upper.

100. A pulling-over machine having, in combination, toe and side grippers, power operated mechanism for effecting updraw movements of said grippers, and means under control of the operator for causing the power operated mechanism to effect additional movements to increase or decrease the updrawing pull of a side gripper independently of the other grippers.

101. A pulling-over machine having, in combination, toe and side grippers, power operated mechanism for effecting updraw movements of said grippers, and means under control of the operator for causing the power operated mechanism to effect additional movements to increase or decrease the updrawing pull of the two side grippers independently of one another.

102. A pulling-over machine having, in combination, toe and side grippers, power operating mechanism for yieldingly updrawing said grippers, and means under control of the operator for causing the power operated mechanism unyieldingly to increase or decrease the updrawing pull of a gripper.

103. A pulling-over machine having, in combination, a toe gripper, side grippers, power operated mechanism for moving said grippers to pull an upper longitudinally and transversely, and means under control of the operator by which said mechanism can be caused to move a gripper positively for increasing or decreasing the pull exerted by 105 that gripper on the upper.

104. A pulling-over machine having, in combination, toe and side grippers, a last rest, power operated mechanism for relatively moving the last rest and the grippers 110 to stretch an upper longitudinally and transversely, and manually controlled means for causing said power mechanism to impart additional relative movements to said parts to increase or decrease the stretching of the 115 upper.

105. A pulling-over machine having, in combination, pulling-over means, tacking means, power operated mechanism to cause the pulling-over means to pull the upper 120 and then come to rest holding the upper under tension and to cause the tacking means to fasten the upper when the machine is restarted, and means under control of the operator to lock the pulling-over means with 125 the upper under tension and hold it until the machine is restarted for tacking.

106. A pulling-over machine having, in

combination, pulling-over means, tacking means, power operated mechanism to cause the pulling-over means to pull the upper and then come to rest holding the upper under tension and to cause the tacking means to fasten the upper when the machine is restarted, and means under control of the operator for causing said power operated mechanism to change the tension on the upper while it is held for inspection and to lock the pulling-over means under the changed tension until the machine is restarted for tacking.

107. A pulling-over machine having, in combination, toe and side grippers, power operated mechanism therefor including a continuously running shaft, means under control of the operator by which said shaft can be made to move a gripper to tension an upper to an extent determined by the operator for the particular upper being treated, and means for locking the gripper in the position to which it is moved.

108. A pulling-over machine having, in combination, a gripper, power operating mechanism, and connections therefrom to the gripper by which to impart an initial pull which can be measured in units of force and, at the option of the operator, a later pull which can be measured in units of length.

109. A pulling-over machine having, in combination, a gripper, power operating mechanism, and connections therefrom to the gripper by which to impart an initial pull which can be measured in units of force and a later pull which can be measured in units of length said connections including means whereby the operator is enabled to control variably during the operation of the machine the extent of said later pull.

110. A pulling-over machine having, in combination, grippers for engaging the fore-part of an upper upon opposite sides of a last, means for moving the side grippers, and separately controllable power-driven mechanism for imparting additional movements to said grippers for increasing or decreasing the pulling strain.

111. A pulling-over machine having, in combination, grippers for engaging the fore-part of an upper upon opposite sides of a last, mechanism for causing the grippers to seize and pull the upper, and manually controllable power-driven mechanism constructed and arranged for moving one gripper to further pull the upper without similarly moving the other gripper.

112. A pulling-over machine having, in combination, grippers movable to seize an upper at opposite sides of a last and pull the upper, yielding connections through which the grippers are caused to apply a yielding pull to the upper, power-driven op-

erating mechanism, and unyielding connections through which the grippers may be thereafter caused by said power-driven mechanism to apply an unyielding pull to the upper.

113. A pulling-over machine having, in combination, grippers for engaging an upper at opposite sides of a last, mechanism through which said grippers are caused to updraw the upper with equal force on the two sides of the shoe, and additional mechanism by which said side grippers may be made to updraw the upper on each side of the shoe positively and to extents separately determined for each side of the shoe by the operator.

114. A pulling-over machine having, in combination, toe and side grippers, mechanism for actuating said grippers to pull an upper longitudinally and transversely, and power-driven mechanism under control of the operator for moving the side grippers to increase or decrease the transverse pull on the upper.

115. A pulling-over machine having, in combination, pulling-over means including side grippers, mechanism for imparting movements to the grippers, and manually controlled power operated mechanism by which to impart other movements to the side grippers independently of the other pulling-over means.

116. A pulling-over machine having, in combination, upper pulling devices including side grippers, mechanism for actuating said devices, and power operated mechanism under control of the operator for actuating the side grippers alone.

117. A pulling-over machine having, in combination, toe and side grippers, mechanism for effecting updrawing movements of said grippers, and power operated mechanism under control of the operator for effecting additional movements to increase or decrease the updrawing of a side gripper.

118. A pulling-over machine having, in combination, grippers for engaging an upper on a last, power operating means for moving said grippers to tension the upper, and means under control of the operator for causing said power means to move one of the grippers alone independently of any movement of the other grippers.

119. A pulling-over machine having, in combination, toe and side grippers, power operating means connected to said grippers to cause them to pull a shoe upper, and manually controlled means by which said power means can be made to move one of the grippers independently of any movement of the others to change the tension of the portion of the upper engaged by said gripper.

120. A pulling-over machine having, in combination, grippers for engaging an up-

- per on a last, power operating means for said grippers, and means under control of the operator as he stands in working position for controlling the application of power 5 to one of the grippers to cause said power means to move said gripper alone relatively to the others to vary the tension of the portion of the upper engaged by said gripper.
- 10 121. A pulling-over machine having, in combination, grippers for engaging an upper on a last, power operating means for said grippers, and means under control of the operator for connecting said power operating means to one of the grippers alone.
- 15 122. A pulling-over machine having, in combination, a gripper for engaging an upper on a last, power driven means for operating said gripper, either to pull the upper or to relax the tension under which the upper is held, and controlling means whereby the operator is enabled to initiate or stop the movement of said operating means at will to produce any desired degree of tension 20 in the portion of the upper engaged by the gripper.
- 25 123. A pulling-over machine having, in combination, a gripper for engaging an upper on a last, means for effecting relative movement of the gripper and the last to tension the upper, power operated means whereby the gripper may be moved subsequently in a direction to relax the tension of the upper; and means enabling the operator to control the extent of such relaxing movement.
- 30 124. A pulling-over machine having, in combination, a gripper for engaging an upper on a last, power operated means for effecting relative movement of the gripper and the last either to tension the upper or to relax the tension, and means enabling the operator to control the extent of such relative movement.
- 35 125. A pulling-over machine having, in combination, grippers for engaging an upper on a last, power driven means for effecting relative movement of the grippers and the last to tension the upper, and power driven means under the control of the operator for moving one or more of the grippers independently to vary the relative tension of different portions of the upper.
- 40 126. A pulling-over machine having, in combination, a gripper for engaging an upper on a last, power driven means for operating said gripper to pull the upper, means enabling the operator to disconnect the gripper at will from said power means, and means for locking the gripper to cause it to hold the upper under tension.
- 45 127. A pulling-over machine having, in combination, a gripper for engaging an upper on a last, power driven means for operating said gripper to cause it to pull the upper unyieldingly, and means enabling the operator to control at will the extent of the pulling movement of the gripper.
- 50 128. A pulling-over machine having, in combination, grippers for engaging an upper on a last, means for effecting relative movement of the grippers and the last to tension the upper longitudinally and transversely, and separate power driven means under control of the operator whereby the relative longitudinal and transverse tension of the upper may be varied.
- 55 129. A pulling-over machine having, in combination, grippers for engaging an upper at opposite sides of a last, means for effecting relative movement of the grippers and the last to tension the upper, and power driven means under control of the operator for effecting relative movement of the grippers to adjust the tensioned upper on the last.
- 60 130. A pulling-over machine having, in combination, a gripper, power driven means for imparting to the gripper updrawing and overdrawing movements, means for locking the gripper, and means for causing the locking means to unlock the gripper only after the overdrawing movement has begun.
- 65 131. A pulling-over machine having, in combination, a gripper for engaging an upper on a last, yielding means for operating the gripper to pull the upper over the last, means for moving the gripper to draw the margin of the upper inward over the bottom of the last, and means for controlling the position of the gripper relatively to the plane of the shoe bottom as it is moved inward.
- 70 132. A pulling-over machine having, in combination, a gripper for engaging an upper on a last, yielding means for operating the gripper to pull the upper over the last, means for moving the gripper to draw the margin of the upper inward over the bottom of the last, and means for subjecting the gripper to positive control to determine its position relatively to the plane of the shoe bottom as it is moved inward.
- 75 133. A pulling-over machine having, in combination, a gripper for engaging an upper on a last, means for operating the gripper to pull the upper over the last comprising an operating member and connections constructed and arranged to permit relative yielding movement between the gripper and said member, means for moving the gripper to draw the margin of the upper inward over the bottom of the last, and means for preventing such relative yielding movement in the gripper operating connections during the initial portion of said overdrawing movement of the gripper.

134. A pulling-over machine having, in combination, a gripper for engaging an upper on a last, means for operating said gripper to pull the upper over the last, means for operating the gripper to draw the margin of the upper inward over the bottom of the last, and means for preventing movement of the gripper toward the plane of the shoe bottom during the initial portion of 10 said overdriving movement.

135. In a pulling-over machine, the combination with a gripper and means for operating the gripper to cause it to pull an upper and to come to rest while holding the 15 upper under tension, of power operated means for imparting at the will of the operator a subsequent movement of variable extent to the gripper, manual means for initiating the operation of said power operated means, and means for preventing movement of said manual means in a direction to cause said movement of the gripper until after the machine has been started for effecting said first mentioned operation 25 of the gripper.

136. In a pulling-over machine, the combination with a gripper and means for operating the gripper to cause it to pull an upper and to come to rest while holding the 30 upper under tension, of means for imparting a supplemental pulling movement to the gripper, manual means for controlling the operation of said supplemental pulling means, and means for locking said manual 35 means against operative movement until after the machine has been started for effecting the first pulling movement of the gripper.

137. In a pulling-over machine, the combination with a gripper, and means for operating the gripper to cause it to pull an upper and to come to rest while holding the upper under tension, of power operated means for imparting a supplemental pulling movement to the gripper, manual means for initiating the operation of said supplemental pulling means, means for normally locking said manual means against movement to initiate said operation, and means incidentally operative to unlock said manual means 45 after the machine has been started for effecting the first pulling movement of the gripper.

138. In a pulling-over machine, the combination with a gripper and means for operating the gripper to cause it to pull an upper and to come to rest while holding the upper under tension, of power operated means for subsequently moving the gripper either to increase or to relax the tension of 50 the upper, manual means for initiating the operation of said power operated means, and means for locking the pulling manual means against movement to initiate said operation

until after the machine has been started for effecting said first mentioned pulling movement of the gripper.

139. A machine of the class described having, in combination, grippers for engaging an upper on a last, constantly driven power operating means, and means under control of the operator for connecting said operating means to one of the grippers alone for moving that gripper independently of any movement of the other grippers.

140. A machine of the class described having, in combination, grippers for engaging an upper on a last, constantly driven power operating means, means for causing said operating means to impart an upper pulling movement to said grippers, and means under control of the operator for effecting connection with said operating means subsequently to move one or more of said grippers independently to vary the tension under which the upper is held.

141. A machine of the class described having, in combination, grippers for engaging an upper on a last, constantly driven power operating means, connections between said operating means and the grippers for operating the grippers to pull the upper, and additional connections manually controllable with respect to each gripper separately for causing said operating means to effect subsequently supplemental movements 95 of the grippers.

142. A machine of the class described having, in combination, an upper engaging gripper, constantly driven power operating means, means for causing said operating means to impart an upper pulling movement to the gripper, and means for causing said operating means to impart subsequently at the will of the operator another movement to the gripper to change the tension under 105 which the upper is held by said gripper.

143. A machine of the class described having, in combination, an upper engaging gripper, constantly driven power operating means, connections between said operating 110 means and the gripper for moving the gripper to pull the upper, and additional connections between said operating means and the gripper for imparting subsequently another movement to the gripper to change the 115 tension under which the upper is held by said gripper.

144. A machine of the class described having, in combination, shoe positioning means, an upper engaging gripper, constantly driven power operating means, means for causing said operating means to effect relative movement of the shoe positioning means and the gripper to pull the upper, and means for causing said operating 120 means subsequently at the will of the operator 125

ator to impart to the gripper a movement to change the tension under which the upper is held by said gripper.

145. A machine of the class described having, in combination, shoe positioning means, an upper engaging gripper, constantly driven power operating means, means for causing said operating means to effect a relative movement of the shoe positioning means and the gripper to pull the upper, and clutch means under manual control for causing said operating means to effect subsequently an additional relative movement of the shoe positioning means and the gripper of an extent determined by the operator to change the tension of the upper.

146. A machine of the class described having, in combination, an upper engaging gripper, a rotatable operating member, means for causing said member to impart an upper pulling movement to the gripper, and manually controllable means arranged to be connected to said rotatable member to cause said member to impart subsequently to the gripper a movement to change the tension under which the upper is held by said gripper.

147. A machine of the class described having, in combination, a plurality of upper engaging grippers, a power-driven gripper operating member, and structural connections extending from said operating member to the respective grippers and movable under separate control for operating said grippers independently of one another to pull the upper.

148. A machine of the class described having, in combination, a plurality of grippers for engaging an upper on a last, means comprising a power-driven member for imparting upper pulling movement to said grippers, and clutch means under control of the operator for connecting said power-driven member to one of the grippers to operate said gripper independently of any movement of the other grippers.

149. A machine of the class described having, in combination, a plurality of grippers for engaging an upper on a last, means comprising a power-driven member and structural connections extending from said member to the grippers and movable for imparting upper pulling movement to said grippers, and controlling means normally positioned to disconnect said grippers from the power-driven member and manually operable to connect one or more of the grippers selectively to said member for operating said gripper or grippers.

150. A machine of the class described having, in combination, a plurality of grippers for engaging an upper on a last, a power-driven gripper operating member, means for effecting operative connection between said

member and the several grippers to operate them in unison to pull the upper, and means under control of the operator for subsequently effecting at will operative connection between said member and one or more of the grippers selectively to change the tension of the upper.

151. A machine of the class described having, in combination, a gripper for engaging an upper on a last, power-driven means for imparting an upper pulling movement to said gripper, connections to said gripper normally idle during said movement of the gripper, and means under manual control for causing power to be applied subsequently through said connections to impart an additional pulling movement to the gripper.

152. A machine of the class described having, in combination, grippers for engaging an upper on a last, power-driven means for imparting upper pulling movement to said grippers, connections to different grippers normally idle during said movement of the grippers, and means under manual control for causing power to be applied subsequently through said connections to one or more of the grippers selectively at the will of the operator to change the tension of the upper.

153. A machine of the class described having, in combination, grippers for engaging an upper on a last, means for moving said grippers to pull the upper, connections to said grippers normally idle during said movement of the grippers, and power-operated means for subsequently operating the grippers through said connections to change the tension under which the upper is held by said grippers.

154. A machine of the class described having, in combination, a plurality of grippers for engaging an upper on a last, means for effecting relative movement of the last and said grippers to pull the upper, and additional means power-operated for subsequently moving one of the grippers alone to change the tension of the upper.

155. A machine of the class described having, in combination, a gripper for engaging an upper on a last, means for effecting a normal relative movement of the last and said gripper to pull the upper, and additional power operated means under manual control for effecting a subsequent relative movement of the last and the gripper to change the tension of the upper variably as determined by the operator during said movement.

156. A machine of the class described having, in combination, grippers arranged to engage an upper at opposite sides of a last, means for operating said grippers to pull the upper, additional operating means comprising power devices connected to the respective grippers, and means for rendering

said devices effective to impart subsequently additional movement to said grippers to change the tension under which the upper is held by the grippers.

5 157. A machine of the class described having, in combination, grippers for engaging an upper on a last, means for operating said grippers to pull the upper, additional operating means comprising power devices 10 connected to the respective grippers, and means for rendering one or more of said devices effective subsequently at the will of the operator to impart movement to a gripper or grippers for changing the tension of 15 the upper.

158. A machine of the class described having, in combination, grippers for engaging the forepart of an upper upon opposite sides of a last, power-driven operating means, 20 connections between said operating means and the grippers for moving the grippers to pull the upper, and additional connections between said operating means and the grippers arranged for manual control after the 25 upper has been pulled to cause said operating means to effect additional movement of the grippers for changing the tension under which the upper is held by the grippers.

159. A machine of the class described having, in combination, grippers for engaging an upper on a last, means for effecting relative movement of the last and said grippers to pull the upper, and power-operated means under manual control for subsequently effecting relative movement of different grippers to adjust the upper relatively to the last.

160. A machine of the class described having, in combination, grippers for engaging an upper at the toe and at opposite sides of the forepart of a last, power-operated means for moving said grippers to pull the upper, and power-operated means under manual control for subsequently effecting relative 45 movement of the side grippers to adjust the upper on the last.

161. A machine of the class described having, in combination, grippers for engaging an upper at the toe and at opposite sides of 50 a last, means for effecting relative movement of the last and said grippers to pull the upper, controlling handles for the respective side grippers, and power-operated connections arranged to be controlled by 55 said handles to enable the operator to cause a relative adjustment of said grippers for shifting the upper on the last.

162. A machine of the class described having, in combination, a gripper for engaging an upper on a last, yieldable means for effecting relative movement of the gripper and the last to pull the upper, means for operating the gripper to draw the margin of 60 the upper inward over the bottom of the

last, and controlling means constructed and arranged to be substituted for said yieldable means to prevent relative yield between the gripper and the last in a direction transverse to the plane of the shoe bottom in response to the pull of the upper as the gripper begins to move inward.

163. A machine of the class described having, in combination, a gripper for engaging an upper on a last, means for effecting relative movement of the gripper and the last to 75 pull the upper comprising mechanism for subjecting said gripper to yielding control, means for operating the gripper to draw the margin of the upper inward over the bottom of the last, and means for substituting a 80 positive control for the yielding control to prevent the gripper from yielding in the direction of the shoe bottom as it is moved inward.

164. A machine of the class described having, in combination, a gripper for engaging an upper on a last, and power operated means for operating said gripper to pull the upper, said means comprising a manually controllable clutch through which movement 90 is imparted to the gripper, said clutch being constructed and arranged to enable the operator to cause the upper to be pulled to the precise extent desired as he observes the action of the gripper upon the upper.

165. A machine of the class described having, in combination, a gripper for engaging an upper on a last, and power-driven operating means for said gripper comprising a clutch through which movement is imparted 100 to the gripper, portions of said clutch being relatively movable at the will of the operator to terminate the operation of the gripper at any point desired.

166. A machine of the class described having, in combination, a gripper for engaging an upper on a last, power-driven means for operating said gripper to pull the upper, manual means for controlling the operation of said power-driven means, and means arranged to be controlled by said manual means for locking the gripper against movement in a direction to relax the tension of the upper.

167. A machine of the class described, having, in combination, a gripper for engaging an upper on a last, power-driven means comprising a manually controllable clutch for operating said gripper to pull the upper, pawl and ratchet mechanism for locking 115 said gripper against retractive movement, and a manually operative member arranged to control both said clutch and said mechanism.

168. A machine of the class described having, in combination, a gripper for engaging an upper on a last, power-driven means for operating said gripper to pull

the upper, means for locking the gripper against retractive movement, and controlling means movable in one direction first to render said locking means effective to hold 5 the gripper and then to render said operating means effective to move the gripper.

169. A machine of the class described having, in combination, a gripper for engaging an upper on a last, means for effecting relative movement of the last and said gripper to pull the upper, means for locking said gripper against movement in a direction to relax the tension of the upper, additional power-operated means for imparting subsequently a movement to the gripper to increase the tension of the upper, and manually operative controlling means movable initially to render said locking means effective to hold the gripper and then to render 20 said additional means effective to move the gripper.

170. A machine of the class described having, in combination, a gripper for engaging an upper on a last, power-driven means for imparting movement to said gripper, manually operative means movable in opposite directions respectively for causing the gripper to be moved by said power-driven means either in a direction to pull 30 the upper or in a direction to relax the tension, and means arranged to be controlled by said manually operative means in its movement in either direction for locking the gripper against movement in a direction 35 opposite to that in which it is to be moved by the power-driven means.

171. A machine of the class described having, in combination, a gripper for engaging an upper on a last, means for operating 40 said gripper to pull the upper, manual means for locking the gripper against movement in a direction to relax the tension of the upper, and power-operated means for subsequently operating said locking means 45 to unlock the gripper.

172. A machine of the class described having, in combination, a gripper for engaging an upper on a last, power-driven means for operating said gripper to pull the 50 upper, means for locking said gripper against retractive movement, manual means movable in one direction first to render said locking means effective to hold the gripper and then by further movement to render 55 said operating means effective to move the gripper, and means affording the operator an indication of that position of said manual means wherein the locking means is effective and the operating means is ineffective.

173. A machine of the class described having, in combination, a gripper for engaging an upper on a last, power-driven means for operating said gripper to pull the upper, means for locking said gripper

against retractive movement, manual means 65 movable in one direction first to render said locking means effective to hold the gripper and then by further movement to render said operating means effective to move the gripper, and means for holding said manual 70 means yieldingly in a position in which the locking means is effective to hold the gripper and the operating means is ineffective to move the gripper.

174. A machine of the class described having, in combination, grippers for engaging an upper on a last, gripper operating members, and means comprising clutches separately controllable for each gripper for transmitting operative movement through 80 said members to the respective grippers.

175. A machine of the class described having, in combination, grippers for engaging an upper at the toe and at opposite sides of a last, power operating means for 85 imparting movement to the side grippers, and manually operative members positioned in proximity to each other within convenient reach of the operator for making or breaking connection between the operating 90 means and the respective grippers.

176. A machine of the class described having, in combination, grippers for engaging an upper at the toe and at opposite sides of a last, power operating means comprising clutches for imparting movement to the side grippers, and manually operative members positioned in proximity to each other for controlling said clutches to cause movement to be imparted to one or both of the 100 side grippers at the will of the operator.

177. A machine of the class described having, in combination, an upper engaging gripper, operating means for said gripper comprising members connected for rotation 105 simultaneously in opposite directions, a power-driven operating member, and means for effecting connection between said operating member and said oppositely rotatable members selectively at the will of the operator 110 for moving the gripper in different directions.

178. A machine of the class described having, in combination, a gripper for engaging an upper on a last, power-driven operating 115 means, controlling means for enabling the operator to render said operating means effective to move the gripper different distances and to terminate the movement at any point desired, and means automatically operative irrespective of the manual control to prevent excessive movement of the gripper.

179. A machine of the class described having, in combination, a gripper for engaging an upper on a last, power-driven operating 125 means under the control of the operator for imparting a movement of indeterminate extent to said gripper, and means automat-

ically operative irrespective of said control to disconnect the gripper from said operating means at a definite point.

180. A machine of the class described having, in combination, a gripper for engaging an upper on a last, power-driven operating means comprising a clutch controllable manually for causing movements of different extents to be imparted to the gripper, and means for operating said clutch to terminate the movement of the gripper at a definite point.

181. A machine of the class described having, in combination, a gripper for engaging an upper on a last, power-driven operating means for said gripper comprising a clutch having a driven member connected to the gripper and a driving member movable by the operator at will into or out of engagement with said driven member, and means for effecting a relative separation of said driving and driven members at a definite point in the movement of the gripper.

182. In a pulling-over machine, the combination with a gripper, of power-driven operating mechanism, manual controlling means for rendering said mechanism effective or ineffective to impart movement to the gripper, a locking device arranged to be controlled by said manual means to render the device effective or ineffective to prevent retraction of the gripper, said manual means being arranged for movement in one direction to disconnect the gripper from the operating mechanism and then by continued movement in the same direction to unlock the gripper, and means for yieldingly opposing such continued movement of the manual controlling means as to unlock the gripper.

183. In a pulling-over machine, the combination with a gripper, of power-driven operating mechanism, a clutch for connecting said mechanism to the gripper or disconnecting it therefrom, manual means for operating said clutch, pawl and ratchet mechanism for locking the gripper against retraction, said manual means being constructed and arranged to control the engagement of the pawl with the ratchet to render said mechanism effective or ineffective to lock the gripper and having a limited movement to release the clutch without affecting the position of the pawl, and means affording the operator an indication of the position of said manual means when the clutch is released and before the position of the pawl has been affected.

184. In a pulling-over machine, the combination with means for gripping an upper on a last and mechanism for effecting relative movement of the gripping means and the last to pull the upper and for then holding the upper under tension, of power operated means for moving the gripping

means in a direction to increase the tension under which the upper is held, manual means for initiating the operation of said power operated means, and mechanism for preventing operative movement of said manual means prior to the initial tensioning of the upper.

185. A pulling-over machine having, in combination, upper gripping means, upper fastening means, power operated mechanism for causing the upper to be pulled and then held under tension by the gripping means and for causing the upper to be fastened by the fastening means when the machine is again started, and means for operating the gripping means to change the tension of the upper and for locking it to hold the upper under the changed tension for the operation of the fastening means.

186. A pulling-over machine having, in combination, upper gripping means, power operated mechanism for causing the upper to be pulled and then held under tension and for causing the gripping means subsequently to overdraw the upper, and locking mechanism arranged to operate upon the gripping means to prevent it from moving in a direction to relax the tension of the upper during the overdraw.

187. A pulling-over machine having, in combination, an upper engaging gripper, power operated means for moving said gripper to pull the upper, and means automatically operative to prevent retractive movement of the gripper from the position to which it is moved by said means.

188. A pulling-over machine having, in combination, an upper engaging gripper, power operated means under manual control for moving said gripper to pull the upper variably as determined by the operator, means automatically operative to lock the gripper against retractive movement from the position to which it is moved by said means, and automatic means for subsequently unlocking the gripper.

189. A pulling-over machine having, in combination grippers for engaging an upper on a last, power operating mechanism and connections for effecting relative movement of the last and said grippers to pull the upper, and manually controlled means for connecting one of the grippers alone to said power operating mechanism to operate said gripper to vary the tension of the upper.

190. An upper pulling machine having, in combination, a gripper, a shoe bottom rest, and means for effecting relative movement of said gripper and rest to pull an upper first yieldingly and then unyieldingly.

191. An upper pulling machine having, in combination, a gripper, power driven means for moving said gripper to pull an upper yieldingly, and additional power driven means arranged to be connected to

said gripper to supplement the yielding pull by an unyielding pull.

192. An upper pulling machine having, in combination, a gripper, and means for imparting upper pulling and overdrawing movements to said gripper to pull the upper first yieldingly and then unyieldingly and for locking the gripper to hold the upper unyieldingly for the overdraw.

In testimony whereof we have signed our **10** names to this specification in the presence of two subscribing witnesses.

ELI BROTHERS.
JOHN T. LANCASTER.

Witnesses:

CHESTER E. ROGERS,
LAURA M. GOODRIDGE.

It is hereby certified that in Letters Patent No. 1,333,536, granted March 9, 1920, upon the application of Eli Brothers, of Lynn, and John T. Lancaster, of Beverly, Massachusetts, for an improvement in "Upper-Pulling Machines," errors appear in the printed specification requiring correction as follows: Page 14, lines 83 and 84, claim 101, for the words "mechanism for effecting updraw movements of said grippers" read *mechanism for updrawing said grippers*, and lines 86 and 87 strike out the words "to effect additional movements"; page 17, line 62, claim 138, for the words "the pulling" read *said*, and line 63 for the word "said" read *the pulling*; and that the said Letters Patent should be read with these corrections therein that the same may conform to the record of the case in the Patent Office.

Signed and sealed this 14th day of September, A. D., 1920.

[SEAL.]

M. H. COULSTON,
Acting Commissioner of Patents.

Cl. 12—4.
